UNITED STATES PATENT OFFICE.

JOHN F. MILLER, OF MONON, INDIANA.

CALF-WEANER.

SPECIFICATION forming part of Letters Patent No. 417,494, dated December 17, 1889.

Application filed March 22, 1889. Serial No. 304,258. (No model.)

To all whom it may concern:

Be it known that I, JOHN F. MILLER, a citizen of the United States, residing at Monon, in the county of White and State of Indiana, have invented certain new and useful Improvements in Calf-Weaners; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to calf-weaners.

15 The object of the invention is to construct a device for the purpose aforesaid that will be simple, cheap, and efficient, and which will be light and not inflict injury, which has so often proved fatal.

20 The improvement consists of the novel features which will be hereinafter more fully described and claimed, and which are shown in the annexed drawings, in which—

Figure 1 is a perspective view showing the 25 application of my invention; and Fig. 2, a perspective view, parts being broken away, of the weaner.

The weaner comprises a nose-apron A, of suitable flexible material, such as ducking or other strong and durable fabric. The nose-strap B is secured to the upper edge of the apron, and between it and the apron is inserted the metallic band C, which stiffens and gives shape to the nose-apron. The re-enforcing piece D, of leather or other stout material, secured to the apron near its upper end

and midway of its edges, has openings d, which come opposite the nostrils of the animal, to permit of free respiration. The metal or leather binding E on the lower edge of the 40 said nose-apron serves to prevent wear and weight the lower edge of the apron, so that the apron will fall across the mouth of the animal when the latter attempts to elevate its head. The lower corners of the apron are 45 rounded and the metal or leather binder extends around the same and up on each side of the head, to prevent lateral displacement of the apron. The head-strap F is secured to the upper end of the nose-apron, substantially 50 as shown.

Having thus described my invention, what I claim, and desire to secure by Letters Patent, is—

1. The combination, with the nose-apron 55 having openings near its upper end, of the re-enforcing piece D, having corresponding openings, substantially as described.

2. The herein shown and described calf-weaner, composed of the nose-apron curved at 60 its lower corners and having a binder at said lower end, the head and nose straps, the curved metal band placed between the nose-strap and the said apron, and the re-enforce D, substantially as set forth. 65

In testimony whereof I affix my signature in the presence of two witnesses.

JOHN F. MILLER.
